UNITED STATES PATENT OFFICE.

WILLIAM H. BRIDGMAN, OF NEW YORK, N. Y.

SHOWER-BATH APPARATUS.

SPECIFICATION forming part of Letters Patent No. 650,503, dated May 29, 1900.

Application filed September 25, 1899. Serial No. 731,514. (No model.)

To all whom it may concern:

Be it known that I, WILLIAM H. BRIDGMAN, a citizen of the United States, residing at New York, in the county of New York and State 5 of New York, have invented certain new and useful Improvements in Shower-Bath Apparatus, of which the following is a full and complete specification, such as will enable those skilled in the art to which it appertains to 10 make and use the same.

This invention relates to shower-bath apparatus; and the object thereof is to provide an improved shower-bath attachment adapted for connection to bath-tubs and embracing 15 improved features of construction, attachment, and adjustment, as fully set forth in the following specification, of which the accompanying drawing forms a part and which shows a vertical transverse section of a bath- 20 tub provided with my shower-bath apparatus.

Referring more particularly to the drawing, I have shown at 12 a bath-tub of the ordinary or any preferred form, and at 6 and 7 two tubes, each of which is provided with a plurality of perforations 9 at one side. Said tubes are preferably of metal or other rigid material and are supported in annular members 17 of clamp devices 18, which comprise rods 19, connected with said annular member 17 and adjustably connected by set or clamping screws 20 with hook-shaped portions 21, which pass about the upper rims or edges of the sides of the tub 12. The binding screws or clamps 20 connect the hook-shaped portions 21 and the rods 19 of the clamping devices 18 by means of annular heads 22, in which said hook-shaped portions and the rods 19 respectively terminate, and it is evident that the rods 19 may be swung 40 in a vertical path to raise or depress the annular portions 17, which support the tubes 6 and 7. By means of the rods 19 a greater play of the tubes 6 and 7 is insured, and a greater versatility of operation thereof is provided. The tubes 6 and 7 are provided with knobs 10, whereby they may be adjusted relatively to the annular members 17 of the rods 19.

It is evident that I may considerably vary the construction and arrangement of elements of my invention as set forth in the foregoing description and shown in the accompanying drawing without departing from the spirit of my invention or sacrificing the advantages thereof. 50

Having fully described my invention, I claim as new and desire to secure by Letters Patent—

1. A shower-bath apparatus, embodying a perforated tube, and devices for detachably 60 and adjustably connecting the same with the rim or edge of the bath-tub, comprising a plurality of rods in the ends of which said tube is turnably supported, hook devices which are passed about the rim or edge of the bath-tub, said rods and hook devices being adjustably connected, means for securing said rods and hook devices in relatively-adjusted positions, and means for adjusting said tube in connection with said rods, substantially as 70 shown and described.

2. A shower-bath apparatus, embodying a perforated tube, and devices for detachably and adjustably connecting the same with the rim or edge of a bath-tub, comprising a plurality of rods provided with annular portions through which said tube is passed, hook devices which are passed about the rim or edge of the bath-tub, said rods and hook devices being provided with heads, and clamping 75 screws or devices which operate in connection with said heads to adjustably connect said rods and hook devices, and means for adjusting said tubes in position in connection with said rods, substantially as shown and de- 80 scribed.

In testimony that I claim the foregoing as my invention I have signed my name, in presence of the subscribing witnesses, this 23d day of September, 1899.

WILLIAM H. BRIDGMAN.
